UNITED STATES PATENT OFFICE.

EDWARD R. WATSON, OF INDIANAPOLIS, INDIANA.

ARTILLERY-PROJECTILE.

1,220,803.

Specification of Letters Patent. Patented Mar. 27, 1917.

Application filed August 5, 1916. Serial No. 113,272.

To all whom it may concern:

Be it known that I, EDWARD R. WATSON, a citizen of the United States, and a resident of Indianapolis, in the county of Marion and State of Indiana, have invented certain new and useful Improvements in Artillery-Projectiles, of which the following is a specification.

My invention relates to artillery projectiles, particularly heavy artillery, and the main object thereof is to provide a projectile which, at a predetermined time after having been discharged from a gun, will itself discharge a plurality of explosive shells simultaneously and, preferably, over an area much greater than would be possible if the projectile was of the usual explosive type.

A further object is to provide means connected with the projectile for discharging the explosive shells at a definite time, and also to provide means for igniting the charges in the explosive shells within said projectile, and a still further object is to provide means insuring the bursting of said shells upon impact with an object, such as an air-craft, a building, a trench, etc., in the event of the shells striking such object before the complete ignition of the bursting charges therein has occurred, or in the event of failure of ignition of the charges within the projectile for any reason.

A further object is to provide a practically unimpeded discharge opening in the projectile for each shell but at the same time presenting a conical head for the projectile to minimize air resistance in its flight.

My invention is fully described in the following specification, of which the accompanying drawings form a part, in which like characters refer to like parts in each of the views, and in which:—

Figure 1 is a longitudinal, axial, section taken through a projectile constructed in accordance with my invention;

Fig. 2 is a section taken on the line 2—2 of Fig. 1;

Fig. 3 is a view of a perforated cup, detached, which I employ in each explosive shell; and

Fig. 4 is a similar view of another form of perforated cup which I employ in conjunction with the foregoing cup.

Referring to the drawings, 5 represents a projectile of any desired dimensions and which may or may not contain a bursting charge 6 but which does provide a longitudi-

nal bore 7 containing an ignition element for the discharge of the explosive shells 8 from the projectile, said shells being four in number in the form illustrated but may be 60 of any desired number, and said bore 7 is terminated at its forward end in proximity to a fuse 9 which may be impact or percussion but which is preferably of the timing type employed in shrapnel.

The bore 7 is shown as on the longitudinal axis of the projectile and connects with four branches 10 each of which is branched at 11 to connect with the respective shell chambers 12, the powder 13 in the bore 7 connecting with the powder 14 in the branches 10 and in turn with the powder 15 in the sub-divisions 11 and these in turn with the powder 16 in the respective chambers 12 for the shells 8.

Each shell 8 consists of a cylindrical casing closed at its rear end and open at its forward end, as shown at 17 and 18, respectively, two bores 19 being provided in the rear end connecting the rear of the shell chamber 12 with the interior or bursting charge chamber 20 of the shell, powder 21 being held in the bores 19 and leads to powder 22 in a cup 23 fitted into the chamber 20, this cup 23 having two bores 24 having 85 powder therein leading to powder 25 in a supplemental cup 26 also fitted into the chamber 20, the latter cup 26 having a centrally arranged tube 27, preferably perforated at its sides, extended forwardly into 90 the chamber 20 for a desired distance into the bursting charge 28.

The forward end of the shell casing is of reduced diameter and screw threaded, as shown at 29, to receive a cap 30 having a 95 chamber 31 for a plurality of balls 32 arranged about a central tube 33 held between the forward end of said cap and a plate 34 fitted into the forward end of the chamber 20, a felt disk 35 being interposed between 100 said plate 34 and the bursting charge 28.

The plate 34 carries a tube 36 extended rearwardly into the chamber 20 and perforated at this end and is extended forwardly into the tube 33 to receive a percussion cap 105 37 in communication with the powder 38 in the tube 36 and adapted to be exploded by a plunger 39 recessed at its inner end and telescoped over the forward end of the tube 36 whereby the plunger is guided in its movement. The plunger 39 extends outwardly of the cap 30 for a desired distance and is pref-

erably recessed at its forward end to provide a sharp rim 40 intended to catch on anything against which the plunger might strike when the shell 8 is in flight and thus 5 explode the percussion cap 37. The plunger is normally held in its forward position by means of a coil spring 41 interposed between the plate 34 and a pin 42 in the plunger, said pin also limiting movement of the 10 plunger forwardly of the shell 8.

The chambers 12 for the explosive shells 8 are shown as forwardly diverging the degree of inclination of which is in the ratio of the length of the shells 8, this being preferable though not imperative in order to increase the effective era of the shells when projected from the projectile, and I cover the open ends of the chambers 12 with a light 15 conical shield 43 which prevents the air resistance which would otherwise obtain.

The bores in the projectile provide, with their contained powder, train fuses for the ignition of the firing charges 16 in the chambers 12 to discharge the shells 8 and, in this 25 discharge, the bores 19 and perforated cups 23 and 26, as well as the perforated tubes 27, with their contained powder, forming train fuses for igniting the respective bursting charges 28.

30 When the shells are exploded, either through the medium of the timing or impact

fuses, the balls 32 are scattered and the shells themselves broken into relatively small fragments forming missiles doing damage over a relatively great area and, with the shells 35 themselves being separated after their discharge from the projectile, the combined effect of all the shells is terrific.

The arrangement of the train fuses shown tends to cause discharge of all the shells 8 40 simultaneously and, with respect to the shells, to cause the latter to explode simultaneously, and my projectile is thus capable of great execution when used against air-craft.

Having fully described my invention, 45 what I claim as new, and desire to secure by Letters Patent, is:—

An artillery projectile, comprising a casing having a plurality of forwardly opening shell chambers, and a shell in each chamber, 50 each shell consisting of a casing for an explosive charge, a plurality of balls in the head thereof, a tube within said head, a percussion cap in said tube and in communication with the explosive charge, and a spring 55 resisted plunger adapted to strike said cap projected forwardly of said shell, the forward end of said plunger being recessed in order to provide a sharp rim adapted to catch on objects in the shell flight instead 60 of deflecting the shell.

EDWARD R. WATSON.
